UNITED STATES PATENT OFFICE.

THOMAS J. LITTLE, JR., OF WOODBURY, NEW JERSEY, ASSIGNOR TO WELSBACH LIGHT COMPANY, OF GLOUCESTER CITY, NEW JERSEY, A CORPORATION OF NEW JERSEY.

GAS-LAMP.

986,300.

Specification of Letters Patent. Patented Mar. 7, 1911.

Application filed May 3, 1909. Serial No. 493,452.

To all whom it may concern:

Be it known that I, THOMAS J. LITTLE, Jr., of Woodbury, in the county of Gloucester and State of New Jersey, have invented a new and useful Gas-Lamp, of which the following is a full, clear, and exact description, reference being had to the accompanying drawings, forming part of this specification, in which—

10 Figure 1 is a side elevation of a lamp embodying my invention; Fig. 2 is a sectional elevation of the same; Fig. 3 is a section on the line III—III of Fig. 2; Figs. 4 and 5 are detail views showing one of the Bunsen pipes or tubes; and Figs. 6 and 7 are detail views hereinafter referred to.

My invention has relation to incandescent gas lamps of the inverted cluster type, the main object of my invention being to provide a lamp of this character having the Bunsen tubes projecting outside of the lamp casing with the adjusting screws for the valves readily accessible from the exterior of the lamp; to provide an improved construction and arrangement of the Bunsen tubes whereby they may be readily removed for cleaning or other purposes without disturbing the burners or mantles; to provide means for preventing undue heating of the Bunsen tubes and of the adjusting screws for the valves and to provide means for preventing flash-backs at the inlet orifices of the Bunsen tubes; and to improve the general construction and arrangement of these and other features of the lamp, as hereinafter fully described.

The nature of my invention will be best understood by reference to the accompanying drawings, in which I have shown one embodiment thereof, and which will now be described, it being premised, however, that various changes may be made in the details of construction and arrangement of the parts, without departing from the spirit and scope of my invention, as defined in the appended claims.

In these drawings, the numeral 2 designates the casing of the lamp which may be of any desired form, being shown as consisting of a cylindrical body portion with outwardly flared upper and lower end portions, the body portion and the lower flared end portion being provided with a plurality of slots or openings 3, for the entrance of air therethrough.

4 designates the mantles and 5 the burner tips which are secured by nipples 6, forming extensions of the lower socket portions 7 of the Bunsen tubes 8. The sockets 7 are secured by screws or other suitable means to the lower flame plate 9, and have their socket portions, which project above the flame plate, inclined obliquely outward, as shown. The lower end portions of the Bunsen tubes fit within these sockets and are removably secured therein by means of studs 10, which engage bayonet slots 11, as best shown in Fig. 4. The upper ends of the Bunsen tubes fit loosely within the valve heads 12, in the manner shown in Fig. 5. 70 This tube is preferably provided with a projecting thumb-piece or lug 13, which may be grasped for the purpose of turning the tubes to disengage the studs or projections 10 from the bayonet slots 11, thereby permitting the tubes to be readily removed and withdrawn from the lamp above the lower flame plate, without in any way disturbing the burners and mantles. I preferably provide each of the tubes with an interiorly located thermostatic control pipe 14, which is in the form of a slotted cone, the fingers formed by the slits being capable of expanding or contracting according to the heat of the burner, to regulate the admission to the burner. 85

Each of the valve heads 12 is connected by a branch pipe 15, with a central supply pipe 16, which extends outwardly into the lamp between the series of draft tubes or chimneys 17. The gas way into the valve head is preferably provided with a plugged opening 18, this plug consisting of a removable screw which can be readily removed for 'cleaning out' purposes. The needle valves 19 have their shafts or stems 20, projecting obliquely outward through the upper ends of the valve heads exterior of the lamp casing, being preferably provided with insulated handles 21, to prevent burning of the fingers in adjusting the valve. The 100 valve stems are preferably made hollow with a plurality of openings 22 to admit air thereto, to prevent undue heating. 23 designates compression springs which are interposed between the handles 21 and the ends 105 of the valve heads for the purpose of taking up any looseness in the threads.

The valve heads are provided adjacent to the gas escape orifice 24 with air admission ports 25. The area of these ports is con- 110

trolled by a rotatable sleeve 26, having an operating projection 27. The sleeve 26 has an outer surrounding wall 28, which extends upwardly and forms a guard around the air inlets to prevent explosions due to the ignition of the gas at the gas-orifice and which produce what is known as flash-backs. It will be seen that the members of this series of Bunsen tubes are arranged between the draft tubes or chimneys 17, at their lower ends, and that they project obliquely outward so that the upper ends of the valve heads and the adjusting screws for the valves are exterior of the casing 2. This not only brings the adjusting screws into accessible position, but it also prevents undue heating of the Bunsen tubes.

29 designates a deflector, whose contracted lower end portion is extended into the central portion of the casing 2, and whose outwardly and downwardly curved upper portion acts to throw the products of combustion outwardly in an annular sheet away from the gas supply pipe. The openings 3 in the casing permit free circulation of air between the chimneys 6, preventing their becoming too hot, and also cooling the center supply pipe.

30 designates the main controlling valve for this supply pipe, and 31 the pilot light valve for controlling the admission of gas to the pilot light supply pipe 32. This valve arrangement forms no part of my present invention, and in so far as the present invention is concerned, any suitable controlling valve mechanism may be employed.

33 designates the globe of the lamp, whose contracted upper portion or neck 34 is extended upwardly within the depending vertical flange 2^a at the lower end of the casing 2. This collar or neck is provided with an encircling metal band 35, which is provided with the insulated radial projecting handles 36, whose shanks engage bayonet slots 37 in the depending flange 2^a. The metal collar 35 is a slotted collar and its ends are detachably secured in any suitable manner. In Figs. 3 and 7, I show them as being secured by metal clips 38, engaging the lugs 39, and having their ends bent backward over said lugs in the manner shown. This enables the metal collar to be readily put on and taken off.

One of the bayonet slots is provided with a locking device (shown in detail in Fig. 6) consisting of a latch 40, pivoted to the flange 2^a at 41, and normally held in closing position by a spring 42. This latch is provided with a projecting knob or handle 43, by means of which it may be readily lifted to release the lock and permit the globe to be removed by rotating it sufficiently to enable the shanks of the handles 36 to pass through the vertical arms of the bayonet slots.

44 is a chain which is connected at one

end to the casing and at the other end to the metal band or ring 35, and which serves to hold the globe suspended while it is being cleaned.

A layer 45 of heat-insulating material, such as asbestos, is preferably interposed between the neck of the globe and the ring or band 35. By the provision of this metal band around the neck of the globe supported in the manner described, I obviate the use of the ordinary screws which impinge upon the glass and which in use are either so loose as to endanger the safety of the globe, or are so tight as to be liable to break the glass. This band holds the globe in position without causing any undue pressure at any one point, all portions of the globe being equally supported so that if a small piece should be broken out, the globe will not fall. In cleaning the globe, this band does not need to be removed. The provision of the handles 36 makes the globe easy to hold, although hot, while it is being cleaned.

While the lamp shown in the drawings is provided with five burners, it will be obvious that my invention is not limited to any particular number of burners, and that this may be varied according to the size of the lamp as desired. It will also be apparent that many changes may be made in the details of construction and the arrangement of the various parts, without departing from my invention.

I claim:

1. A gas lamp of the character described, having a plurality of burners, a plurality of vertical draft tubes or chimneys, and Bunsen tubes projecting obliquely upward and outward between the chimneys and having their upper end portions extending through the lamp casing to the exterior thereof, substantially as described.

2. A gas lamp of the character described, having a plurality of burners, a plurality of draft tubes or chimneys arranged around a central gas supply pipe, and a plurality of Bunsen tubes leading to the burners and extending obliquely upward and outward between the draft tubes or chimneys and having their upper ends projecting exteriorly of the lamp casing, substantially as described.

3. A gas lamp of the character described, having a lower flame plate provided with a socket projecting from its upper side to receive a Bunsen tube, a support for said plate, a gas supply pipe, a nipple projecting through the plate to receive a gas burner tip, and a removable Bunsen tube supported on the socket and the gas supply tube, substantially as described.

4. A gas lamp of the inverted type having a lower flame plate, a support for said plate, a socket member secured to said plate to receive a Bunsen tube and having a depending nipple projecting through the plate and

- threaded to support a burner tip, substantially as described.
5. A gas lamp of the inverted type having a lower flame plate provided with an obliquely extending socket member, and a Bunsen tube removably held in said socket member and arranged to be removed without disconnecting the socket from the flame plate, substantially as described.
- 10 6. An inverted gas lamp of the cluster type having a lower flame plate, a plurality of socket members connected thereto, said members having socket portions projecting obliquely upward and outward to receive 15 Bunsen tubes and also having each a depending nipple, and burner tubes secured to said nipples, substantially as described.
7. An inverted gas lamp having a burner support provided with an oblique socket member communicating with the burner, a Bunsen tube removably held at its lower end in said socket member, and a gas and air chamber into which the upper end portion of said tube loosely extends and which is 25 provided with a regulating valve, substantially as described.
8. An inverted gas lamp having a plurality of burners, a plurality of draft tubes or chimneys, and a plurality of Bunsen tubes extending obliquely upward and outward between the chimneys, said tubes being removable without disturbing the burner man-
- 30 tles, substantially as described.
9. A gas lamp of the character described, having a plurality of socket members, a plurality of upwardly and outwardly extending removable Bunsen tubes loosely supported therein, valve heads for said tubes and into which they loosely extend at their upper 35 ends, a central supply pipe, and branch pipes connecting the central supply pipe with the valve heads, substantially as described.
10. A gas lamp of the character described, having a lower flame plate, a plurality of socket members connected thereto, Bunsen tubes detachably secured in said socket members, and valve heads with which the upper 40 ends of said tubes are removably engaged, substantially as described.
11. In a gas lamp of the character described, a flame plate having an oblique socket member connected thereto, a bayonet slot in the wall of its socket, a Bunsen tube 45 removably engaging said socket and having a projection engaging said slot, together with a valved supply head with which the upper end of the tube is loosely engaged, substantially as described.
- 60 12. In a gas lamp of the inverted type, a flame or burner plate having a burner supported thereby and depending therefrom, a Bunsen tube for supplying the burner, and supporting means for said tube with which the tube has a loose engagement and from
- which it can be disengaged and removed without disturbing the burner nozzle, substantially as described.
13. In a gas lamp of the inverted type, a gas supply member, a burner, and a Bunsen tube leading from the gas supply member to the burner, said tube having a loose detachable connection with both the supply member and the burner and capable of removal without disturbing the burner nozzle, substantially as described.
14. In a gas lamp of the inverted type, a gas supply member, a burner, and a Bunsen tube leading from the gas supply member to the burner, said tube having a loose detachable connection with both the supply member and the burner and capable of removal by combined vertical and lateral movement without disturbing the burner nozzle, substantially as described.
15. A lamp of the character described having a plurality of burners, a plurality of vertical draft tubes or chimneys, a supply pipe arranged centrally of said tubes or chimneys, a plurality of Bunsen tubes leading to the burners and extending obliquely upward and outward intermediate of the draft tubes or chimneys, and a casing surrounding the tubes or chimneys and having openings through which the upper end of the Bunsen tubes project, substantially as described.
16. A lamp of the character described having a plurality of burners, a plurality of vertical draft tubes or chimneys, a supply pipe arranged centrally of said tubes or chimneys, a plurality of Bunsen tubes leading to the burners and extending obliquely upward and outward intermediate of the draft tubes or chimneys, a casing surrounding the tubes or chimneys and having openings through which the upper end of the Bunsen tubes project, and a deflector above the draft tubes arranged to deflect the products of combustion outwardly away from the central supply pipe, substantially as described.
17. In a gas lamp, a burner plate, a burner supported thereby, and a Bunsen tube for supplying the burner, said tube having a loose detachable engagement with said plate, substantially as described.
18. In a gas lamp of the inverted type, a burner plate having a socket on its upper side, and a Bunsen tube detachably secured in said socket and an independent support for the burner plate; substantially as described.
19. In a gas lamp of the inverted type, a burner plate having a socket on its upper side, a Bunsen tube removably held in said socket, an independent support for the burner plate, and a gas nozzle with which the upper end of the tube is separably engaged; substantially as described.

20. In a gas lamp of the inverted type, a flame or burner plate having a burner nozzle secured to and depending therefrom, said plate also having a seat for a Bunsen tube, and a Bunsen tube loosely and removably engaging said seat and removable without disturbing the burner nozzle, substantially as described.
21. In a gas lamp of the inverted type, a flame or burner plate having a burner nozzle secured to and depending therefrom and having a seat on its upper surface, a gas supply member located above the plate, and
- a Bunsen tube loosely engaging said seat at its lower end and the gas supply member at 15 its upper end, said tube being removable upwardly within said member to permit it to be disengaged from said seat, substantially as described.
- In testimony whereof, I have hereunto set 20 my hand.

THOMAS J. LITTLE, JR.
